UNITED STATES PATENT OFFICE.

WILLIAM HENRY BEEHLER, OF BALTIMORE, MARYLAND, ASSIGNOR TO WILLIAM BEEHLER, INC., OF BALTIMORE, MARYLAND, A CORPORATION OF MARYLAND.

FOLDABLE UMBRELLA.

1,094,633.

Specification of Letters Patent. Patented Apr. 28, 1914.

Application filed December 4, 1909. Serial No. 531,395.

To all whom it may concern:

Be it known that I, WILLIAM HENRY BEEHLER, a citizen of the United States, and resident of Baltimore, in the State of Maryland, have invented certain new and useful Improvements in Foldable Umbrellas, of which the following is a specification.

My invention relates to umbrella construction by means of which the tip or ferrule 10 end of an umbrella may be removed from normal position and folded alongside the umbrella. The principal object of this is to shorten the umbrella and permit it to be packed in a trunk or suit-case.

Umbrellas embodying my invention will 15 usually be made with removable or foldable handles to permit further shortening of the umbrella. My type of folding construction may in many cases be applied to the handle ends, but such adaptations will 20 be apparent to persons skilled in the art and they will not be herein particularly described.

It is evident that when the tip is in its 25 removed or folded position any projection of the rod or extension therefrom beyond the end of the cover increases the folded length of the umbrella.

An important object of my invention is 30 to so construct the umbrella and folding tip that the over-all length of the folded umbrella is as small as possible and so that the total length of the folded umbrella is no greater or very little greater than the dimensions of the cover require.

An umbrella of my construction, because 35 of the absence of any considerable projection beyond the end of the cover when folded, may be packed straight in a trunk or suit-case having an inside length only slightly greater than the length of the ribs.

Further objects of my invention are to 40 enable the foregoing advantages to be realized by means of a simple and cheap construction, and also to provide means of fixing the detachable tip in position which will automatically take up any wear or play which may appear in the parts, and also to provide a new and advantageous combination 45 of the rod, notch, and finishing cap, designed to coöperate with other features of the invention and also having utility in separate applications.

The accompanying drawing shows an ex- 50 amplefying form of the invention which is

the best that I have up to the present time devised; but it is to be understood that the invention is capable of embodiment in other forms.

In the drawing, Figure 1 is a longitudinal section of the portion of an umbrella rod distant from the handle, only the necessary parts being shown to make the relation of my invention to an ordinary umbrella clear. Fig. 2 is a longitudinal section showing the tip end in folded position.

Reference character 1 designates the rod and 2, the notch secured thereon and having a portion projecting beyond the end of the rod somewhat, as at 3. The rod and notch, 7 taken together, are sometimes identified in the claims as a "shaft-structure" and it is observed that this shaft structure has a tubular form, the bore of the tube being open at the end toward the tip. The ribs 4 are secured in the notch in any usual or suitable way. The extended portion 3 of the notch may conveniently be provided with an exterior screw-thread 6 upon which the finishing cap 5 is screwed. Otherwise, the cap may be brazed or secured to the notch in any other convenient way. It is not essential to the main purpose of the invention that the finishing cap be secured to the notch. It may in some cases be fixed to the tip.

The tip or "ferrule-end" 7 has an extension or dowel 8 adapted to enter the bore of the shaft-structure or rod 1 and a screw 8^a, adapted to engage an internal screw 9 formed in the notch. Within the rod is a slider or shank 10, provided at the inner end with a shoulder 11. The slider is pivoted at the opposite end to a link 13, and the link is in turn pivoted to the extension or dowel 8. A stop 12 is provided in the rod to limit the outward movement of the shank or slider, 10. This stop may be formed by indenting the rod, as shown.

Fig. 1 shows the tip in normal position with screw 8^a engaging the internal screw 9 of the notch. The tip is folded by rotating it in relation to the rod, thus disengaging the screw from the screw-socket in the notch. The tip is then pulled out until shoulder 11 on slider 10 encounters stop 12, and the tip is folded down alongside the umbrella as shown in Fig. 2. It is evident that the umbrella when folded must be at least as long as the distance from the points of the ribs.

to the end of the notch. The only increase over this minimum length required in the structure described is that of the short extension 3 of the notch. This amounts to a small fraction—less than one-half—an inch.

My invention is not limited to the specific combination of rod, notch and screw-thread arrangement shown, but this particular form of the invention is a valuable one because of 10 the cheap and efficient manner in which the rod, notch and finishing cap are assembled, and because this construction is well adapted to accommodate itself to the desired form of the folding parts. In replacing the tip, 15 the screw is always set up tight, and play or looseness that would otherwise gradually appear is thus taken up without special attention on the part of the user.

The structure described permits the use of 20 metal tubing of standard size for the rod, and at the same time avoids breakages and other disadvantages which occur if it is attempted to internally screw-thread the rod. The method of securing the tip to the 25 rod also provides very great strength at the joint and, in fact, the part of the frame structure adjacent to the joint is stronger than the rest of the rod. A screw thread of ample size and strength to hold the tip is 30 permitted by the fact that this thread is formed in the extension of the notch and, moreover, this thread can be easily made and can be immune to the effects of moisture, because it is possible, and usually prefer- 35 able, to form the tip of relatively soft and non-rusting metal, such as a brass composition, instead of steel.

I claim:

1. In an umbrella, the combination of a 40 rigid hollow metallic rod, a notch thereon extending beyond the end of the rod and having an internal screw thread reaching from the end of the extension approximately to the end of the rod and of an inner di-

ameter approximately the same as the outer 45 diameter of the rod, a removable tip screw threaded to engage the internal thread in the notch, a dowel extending from the tip, a slider within the rod provided with a head at its inner end, and a link pivotally connected to the slider and the tip dowel, the rod being provided with a stop at some distance from the end thereof to engage the slider head.

2. In an umbrella, the combination of a 55 rigid hollow metallic rod, a notch thereon extending beyond the end of the rod and having an internal screw thread, a removable tip screw-threaded to engage the internal thread in the notch, a member extending from the tip, a slider within the rod provided with an abutment at its inner end, and a link pivotally connecting the slider to said member, the rod being provided with a stop to engage said abutment and limit the 60 outward movement of the slider.

3. In an umbrella, the combination of a 70 tubular metallic rod, a notch thereon having a portion extending beyond the end of the rod, said extended portion having an internal screw thread, a removable tip having a screw to engage said internal thread, a slider within the rod, a link connecting the slider with the tip, and a stop to engage the slider and limit its outward movement. 75

4. In an umbrella, the combination of a 80 tubular metal rod, a notch structure thereon having a portion extending beyond the end of the rod, a removable tip having a screw engageng an internal thread in said extended notch portion, a slider within the rod, a stop for the slider, a link connecting the slider with the tip and a finishing cap screwed upon the extended end of the notch.

WILLIAM HENRY BEEHLER.
